Primary Examiner — Robert M Spear*Assistant Examiner* — Ryan Harvey(74) *Attorney, Agent, or Firm* — Wolf, Greenfield & Sacks, P.C.**CLAIM**

The ornamental design for a rear shock absorber for a bicycle, as shown and described.

DESCRIPTION

FIG. 1 is a top front perspective view of a rear shock absorber for a bicycle;

FIG. 2 is a right side view of the rear shock absorber for a bicycle of FIG. 1;

FIG. 3 is a front view of the rear shock absorber for a bicycle of FIG. 1;

FIG. 4 is a left side view of the rear shock absorber for a bicycle of FIG. 1;

FIG. 5 is a rear view of the rear shock absorber for a bicycle of FIG. 1;

FIG. 6 is a bottom view of the rear shock absorber for a bicycle of FIG. 1; and,

FIG. 7 is a top view of the rear shock absorber for a bicycle of FIG. 1.

The broken lines illustrate portions of the article that form no part of the claimed design.

1 Claim, 6 Drawing Sheets---
